UNITED STATES PATENT OFFICE.

ALBERT G. SCHERER, OF CHICAGO, ILLINOIS, ASSIGNOR TO THE EXCELSIOR STEEL FURNACE COMPANY, OF CHICAGO, ILLINOIS, A CORPORATION OF ILLINOIS.

COMBINED HOT-AIR AND COLD-AIR REGISTER.

1,329,803.

Specification of Letters Patent.

Patented Feb. 3, 1920.

Original application filed October 23, 1918, Serial No. 259,357. Divided and this application filed May 19, 1919. Serial No. 298,080.

To all whom it may concern:

Be it known that I, ALBERT G. SCHERER, a citizen of the United States, and resident of Chicago, in the county of Cook and State 5 of Illinois, have invented certain new and useful Improvements in Combined Hot-Air and Cold-Air Registers, of which the following is a full, clear, and exact specification.

10 My invention has relation to a register through one section of which hot-air is discharged from a conduit leading from the furnace or heater, and through another section of the same register cold-air is within 15 drawn from the room to the furnace or heater where it is reheated for circulation.

The present application is a continuation of, and the subject-matter hereof is divided out of the co-pending application filed by 20 me on October 23, 1918, Serial Number 259,357, for improvements in register structures.

The structure disclosed in the present application is especially adapted for use where 25 a register of this type is to be positioned in the floor of the room to be heated away from the walls and usually above the heating element, known as a "pipeless" furnace or re-heater.

30 In heating apparatus of this character the circulation of air is accomplished by withdrawing the cold-air from the floor of the room through one section of a floor register, and passing this air down around the heating 35 element of the furnace after which the reheated air is discharged into the room through another section of the same floor register. Floor registers for pipeless furnaces are usually flat and of circular or rec- 40 tangular outline and on account of their extreme size usually occupy a valuable or desirable area in the center of the room being heated. It is also undesirable to place furnishings in close proximity to such 45 a register because of the dampering effect upon the currents of air being discharged from and moving toward it. Consequently the occupant of the apartment must leave the register and the space contiguous thereto 50 to bare, which, of course, presents an unsightly appearance to the room. It is, therefore, one of the objects of my invention to provide a register structure for the floor of a room or apartment that is compact and

neat in appearance and which, owing to its 55 construction, may be utilized as a table or stand, all of which may be done without hindering the effectiveness of the structure for heating the room.

It has been found by extensive experimentation that the ordinary type of flat register divided for the purpose of both receiving and discharging air is lacking in efficiency because of the fact that the oppositely moving currents of air interfere or hinder the 60 movement of each other, and to this end it is another object of my invention to provide a combined hot-air and cold-air register structure from which the hot-air will discharge 65 in an upward and outward direction and radial from all sides of the register, while the cold-air will be received through the lower section of the register radially from all directions below the current of discharging hot-air. As is well known an increase 70 in the height of a chimney increases the draft, and this is true with stacks for delivering heated air. My present structure, besides providing an aperture which secures 75 an easier discharge and better distribution 80 of the hot-air, adds to the length of the hot-air discharge duct which in itself secures an increased efficiency.

Other objects of my invention will be 85 obvious to other persons skilled in this art after an understanding of my invention is had, among which are the provision of a register structure that is compact in construction, dependable in operation, economical to manufacture and install, and novel 90 in arrangement. I prefer to accomplish the divers objects of my invention in substantially the manner and by the means hereinafter fully described and as more particularly pointed out in the claims, reference 95 being now made to the accompanying drawings that form a part of this specification and which are in a sense merely diagrammatic for the purposes of convenient illustration.

In the drawings:

Figure 1 is a vertical elevation of a register structure adapted to be positioned in the center of a room to be heated and to be utilized as a table.

Fig. 2 is a vertical axial section thereof on line 2-2, Fig. 1.

Fig. 3 is a perspective of the upper por-

tion of the table showing the manner of extending or enlarging the same.

Fig. 4 is a perspective of the underneath portion of the extension boards employed in making the extension of the table.

Fig. 5 is an enlarged vertical section of the upper portion of the table leg employed in the structure illustrated in Figs. 1 to 3.

Fig. 6 is an enlarged transverse section of the leg shown in Fig. 5.

Fig. 7 is an enlarged vertical section of the intermediate strap and upper edge of the baffle or deflector mounted thereon.

It may be desirable as well as necessary to position the register in the center of a room owing to the location of the furnace in the building in order to obtain the most direct currents thereto, and in this event, I have designed a structure wherein the grilles, deflectors and hot and cold-air passage-ways are installed between the legs and below the top of a suitable novel table structure which may be utilized for divers purposes.

The top 75 of the table is preferably round, and has suitable upright legs 76 which are also adapted to carry the upper and intermediate straps 77 and 78, respectively, that are circular or ring shape and have their external beads fitted into suitable transverse grooves made in the inner portions of the legs. A lower L-section strap or ring 79 is also employed in the same manner as the corresponding element in the other types with the horizontal flange resting upon the floor, as set forth in my co-pending applications, and the upper and lower cylindrical plates 80 and 81, respectively forming the reticulated grilles for the hot and cold-air passages, are positioned upon the inside of the legs 76 and are supported and extend between the upper and intermediate straps 77 and 78, and between the intermediate and lower straps 78 and 79. There are four sections of these reticulated walls in both the upper and the lower grilles and the end edges thereof meet each other at the vertical plane of the legs and back of the same, as shown in Fig. 6. In order to join said plates together their meeting edges are provided with lateral flanges or ears 80^a that are apertured and are adapted to be drawn toward each other by bolts 80^b, as shown, while the rear surface of the legs are provided with longitudinal grooves 81^a to accommodate these members.

A hot-air deflector 82 of inverted conical shape is positioned immediately below the table top and is supported upon the upper strap 77 by bending the upper edges 83 of the converging walls of said deflector down over the upper edge of said strap. I have found it desirable to fill the conical deflector with sand or like heat retaining ma-

terial which will store up and retain a quantity of heat so that when the furnace is running under ordinary conditions this sand will become heated, and when the furnace is shut down, as is usually done at night, 70 this material will continue to heat the air that rises through the pipe from the furnace.

The walls 84 of the hot-air passageway from the furnace extend up into the shell 75 formed by the grilles 80 and 81, and the upper portions of said walls are flared outwardly as at 85, toward the intermediate strap 78 and have their edges 86 bent down over the upper edge of this strap (as shown 80 in Fig. 4 of the drawings) in order to secure these walls in position and to provide a cold-air passage-way exteriorly of said hot-air passageway between the same and the lower grille 81 as well as a hot-air discharge section in the upper grille 80. The lower portions of the hot-air and cold-air passage-ways communicate with the furnace structure in the usual manner, and do not need detailed description here.

In connection with the table top I have shown in Figs. 3 and 4 details of a suitable extension whereby the side of the table may be increased in diameter so that it may be used as a dining table, or the like. To this end, I provide suitable slides 87 positioned radially and having chamfered longitudinal edges, as shown, so that they may be moved in correspondingly shaped runways or guide-ways in the under surface of the table-top 75. Suitable extension boards 88 of quadrant shape are provided having their inner edges conforming in curvature with the contour of the edge of the top against which they are adapted to be fitted when in use. Each extension board is provided upon one end with a longitudinally projecting shelf 89 upon its under side and projects beyond the end edge of the extension board so that it will be disposed underneath the adjacent portion of the next board when in position. Dowels 90 are provided underneath each board adapted to fit into corresponding recesses 91 in the slides, and the opposite ends of said boards are also provided with dowels 92 adapted to fit into recesses 93 in the edge of the adjoining extension board. When these extension boards are assembled in the manner shown in Fig. 3 of the drawings, a table of much larger proportions is provided and around which persons may comfortably seat themselves.

The lower ends of the table legs 76 are fitted into suitably shaped sockets 94 secured to and projecting out from the lower 125 strap or ring 79 and their upper ends, which terminate a short distance below the top, are retained against the grilles by inverted L-shaped plates 95 secured to and positioned on the upper strap 77 so that their hori- 130

zontal members fit across the tops of the legs and are fastened in any suitable manner.

Preferably, the lower portion of the upper strap above the bead thereon projects above the tops of the legs so that a suitably inclined shield 96 may be mounted upon said bead in order that it will incline outwardly to engage the bottom surface of the table top, and said shield has perforations or apertures 97 adjacent the top to provide ventilation in the deflector above the sand. Conveniently shaped corner brackets 98 are secured to the tops of the legs and incline outwardly to the edge of the table top where they are fastened thereto to prevent the removal of said top.

What I claim is:—

1. A register comprising a table top, legs supporting the same a distance above the floor, a reticulated shell connecting said legs below said top and providing an interior chamber, a cold-air pipe connected to the lower edges and having radial communication with said shell, and a hot-air pipe extending up into said interior chamber and discharging radially in all directions through said shell above said cold-air pipe.

2. A register comprising a table top, legs supporting the same a distance above the floor, a reticulated shell connecting said legs below said top and providing an interior chamber, a cold-air pipe connected to the lower edges of said shell and adapted to receive the cold-air through the lower half of said shell, and a concentric hot-air pipe extended up into said interior chamber and discharging radially from said shell through the upper portion thereof.

3. In a register, the combination with a table structure consisting of a top and supporting legs, of a cylindrical reticulated shell connecting said legs and provided with circumferential inlet and discharge sections, a cold-air pipe leading to said inlet section, and a hot-air pipe leading to said outlet section.

4. In a register, the combination with a table structure consisting of a top and supporting legs, of a cylindrical reticulated shell connecting said legs; said shell provided with a circumferential cold-air inlet section in its lower portion and a circumferential hot-air outlet section in the portion above said inlet section, a cold-air pipe below and communicating with the lower end of said shell, and a hot-air pipe disposed concentrically within said cold-air pipe and discharging through the upper portion of said shell with its upper portion flared outwardly and engaging the same intermediate the top and bottom thereof.

5. In a register, the combination with a table structure consisting of a top and supporting legs, of a cylindrical reticulated

shell connecting said legs; said shell provided with a circumferential cold-air inlet section in its lower portion and a circumferential hot-air outlet section in the portion thereof above said inlet section, a cold-air pipe below and communicating with the lower end of said shell, a hot-air pipe disposed concentrically within said cold-air pipe and discharging through the upper portion of said shell with its upper portion flared outwardly and engaging the same intermediate the top and bottom thereof, and a deflector depending from the upper edges of said shell with its walls converging downwardly into said hot-air pipe.

6. In a register, the combination with a table structure consisting of a top and supporting legs, of a cylindrical shell connecting said legs and provided with inlet and discharge sections, and concentric pipes leading to said shell the outer pipe whereof is adapted to receive the cold-air passing into said shell through the inlet section and the inner pipe whereof being flared outwardly to engage said shell and discharging hot-air through the outlet portion of said shell.

7. In a register, a top member, legs supporting the same, upper, lower and intermediate straps connecting said legs, an inverted conical deflector below said top having the outer edges of its walls supported upon said upper strap, a second truncated conical deflector below the aforesaid deflector the upper edges whereof are supported upon said intermediate strap, a hot-air pipe communicating with the truncated end of the last-mentioned deflector, and a cold-air pipe outside of and concentric with said hot-air pipe and connected to said lower strap.

8. In a register, a top member, legs supporting the same, upper, lower and intermediate straps connecting said legs, an inverted conical deflector below said top having the outer edges of its walls flanged downwardly and resting upon said upper strap, an inverted truncated conical deflector below the aforesaid deflector the upper edges whereof are flanged downwardly and rest upon said intermediate strap, a hot-air pipe communicating with the truncated end of the last-mentioned deflector, a cold-air pipe outside of and concentric with said hot-air pipe and connected to said lower strap, and reticulated plates fitted between said upper and intermediate straps and between said lower and intermediate straps.

9. The combination with a discharge-pipe of a furnace, of a table top having supporting legs and adapted to be positioned adjacent an outlet of said pipe, and a deflector disposed below said table top and positioned to deflect the air discharged from said pipe and from a plurality of sides laterally out from under said table top.

10. The combination with a discharge-pipe of a furnace having an outlet, of a table positioned adjacent said outlet, and a deflector mounted on said table adapted to deflect the air discharged through said outlet away from said table.

11. The combination with a furnace discharge-pipe provided with an outlet, of a table disposed adjacent said outlet and the top whereof is above the latter, and a de-

flector carried by the table having walls that incline upwardly and outwardly away from said outlet.

Signed at Chicago, county of Cook, and State of Illinois, this 12th day of May, 1919. 15

ALBERT G. SCHERER.
